WATCH CHAIN ORNAMENT

Emilio Rios Badillo, Detroit, Mich.

Application November 7, 1952, Serial No. 22,187

Term of patent 14 years

(Cl. D45—17)

To all whom it may concern:

Be it known, that I, Emilio R. Badillo, a citizen of the United States, residing in Detroit, in the county of Wayne and State of Michigan, have invented a new, original, and ornamental Design for a Watch Chain Ornament, of which the following is a specification; reference being had to the accompanying drawings, forming a part hereof.

Figure 1 is a front elevational view of a watch chain ornament, showing my new design;

Figure 2 is a top plan view thereof;

Figure 3 is a bottom plan view thereof; and

Figure 4 is a transverse sectional view thereof taken along the line 4—4 of Figure 1.

The dominant features of my design reside in those portions shown in full lines.

I claim:

The ornamental design for a watch chain ornament, as shown and described.

EMILIO RIOS BADILLO.
